UNITED STATES PATENT OFFICE

2,493,701

BOX OR CRATE

Arthur C. Thompson, Montreal, Quebec, Canada

Application January 18, 1946, Serial No. 641,934

1 Claim. (Cl. 217—5)

1

This invention relates to improvements in a box or crate composed of prefabricated wall members and is applicable to wooden boxes of the solid wall type or to crates of the slatted wall type.

The salient feature of the invention consists in the provision of a box or crate in which each prefabricated end wall is interlocked with prefabricated side walls or with prefabricated top and bottom walls by four interlocking cleats arranged in rectangular formation, two parallel cleats at each end of the box or crate being formed with mitered ends flatly engaging bevelled longitudinal side edges of the two remaining cleats located at the same end of the box or crate to thereby provide an interfitting or interlocking arrangement of cleats which effectively secures the end walls against displacement relative to the side walls and which also enables the component walls of the box or crate to be rapidly secured together in an assembled relation with a minimum amount of nailing. In this connection it may be noted that two parallel cleats at each end of the box or crate constitute component elements of the prefabricated end wall and that the two remaining cleats with which the end wall cleats are interlocked constitute component elements of two prefabricated opposing side or top and bottom walls of the box.

Other characteristic features and advantages of the invention will be more readily understood from the following detailed description taken in connection with the accompanying drawings in which:

Fig. 1 is an end view of a solid wall box embodying my invention.

Fig. 2 is a vertical sectional view taken along the section line 2—2 of Fig. 1.

Fig. 3 is a perspective view of one of the end walls viewed from the outside.

Fig. 4 is a perspective view of one of the side walls viewed from the inside.

Fig. 5 is a fragmentary perspective view showing a portion of one end wall and a portion of one side wall with the walls in juxtaposition.

The wooden box shown in the illustrated embodiment of the invention comprises prefabricated end walls 5, side walls 6, top wall 7 and bottom wall 8. Upper and lower horizontal cleats 9 are provided as component elements of each prefabricated end wall 5. These cleats 9 extend across the full width of the outer side of the end wall flush with the upper and lower edges thereof. The inner longitudinal edges of the cleats 9 are bevelled to provide bevel surfaces 10 facing toward the end wall 5. A pair of vertically extending cleats 11 are fitted between the end portions of the cleats 9 at each end of the box. The cleats 11 constitute component elements of end portions of the prefabricated side walls 6

which project beyond the outer side of the end wall 5. The upper and lower ends of the cleats 11 are mitered as indicated at 12 to conform to and fit flatly against the bevelled edges 10 of the cleats 9. The prefabricated top and bottom walls 7 and 8 are each secured in place by four corner nails 13. As here shown each nail 13 is driven through an end portion of one of the cleats 9 and into the mitered end portion 12 of the engaging cleat 11. It will be understood that other well known devices instead of nails may be used for securing the prefabricated end, side, bottom and top walls in assembled positions. The cleats 11 are thus secured against outward lateral movement thereof relative to the cleats 9. Since the mitered ends 12 of cleats 11 fit between the bevelled surfaces 10 of cleats 9 and the outer side of end wall 5, it will be seen that each end wall is securely held against inward, outward or vertical movement relative to the side walls 6.

The described rectangular arrangement of interfitting cleats whereby each end wall of the box is interlocked with two remaining walls, such as the side or the top and bottom walls greatly increases the strength and shock absorbing resiliency of the box. In this connection it will be understood that, in order to obtain the benefits of the increased strength and shock absorbing resiliency afforded by the present invention, two parallel cleats at each end of the box must be carried by the end wall and disposed in rectangular interfitting relation with the two remaining cleats which are carried, respectively, by opposite side or by opposing top and bottom walls of the box. The bevelled cleats are preferably carried by the end wall and the co-acting mitered cleats by the side and top or bottom walls. Another advantage of the present invention is that the rectangular interfitting arrangement of cleats, whereby each end wall is interlocked with the side or with the top and bottom wall, reduces the amount of nailing required in prefabricating and securing together the component walls of the container. This is due to the fact that any shock stresses imposed on the nails securing the component walls of the container and on the nails securing the cleats of the end walls to the cleats of the sides or top and bottom walls, are evenly divided among the nails in a desirable manner by the rectangular interfitting arrangement of the cleats.

The crate type of container does not vary from the construction described in connection with the wooden box except that the side walls and the top and bottom walls may be made of slats. Instead of solid panel the slats of the side walls will be secured to the cleats which overlap the end panels and are interlocked with the cleats and carried thereby.

It will be apparent from the description given

above that the box or crate is of very simple construction. The cleats and the panels or slats used in forming the prefabricated end walls and side walls are all machined by simple straight line cutting. These prefabricated end walls and side walls, top and bottom walls can be shipped in the flat in very small packages and can be readily assembled by the packer through the aid of unskilled labor.

It is obvious that minor changes in the details of the prefabricated units may be made without departing from the spirit of the invention as set forth in the appended claim.

I claim:

A box or crate comprising prefabricated bottom, top, side and end walls, each prefabricated end wall including a panel and a pair of parallel cleats extending transversely across the upper and lower portions of the panel at the marginal edges thereof, each cleat being formed with a beveled surface at each end overlying and facing toward said panel, each side wall including a panel and a pair of cleats extending vertically of the side wall across the ends of the side wall and disposed on the inner face thereof so as to over-

lap the end walls, the ends of each side wall cleat being formed with a mitered bevel conforming to the beveled surface on the end wall cleats and interposed between the end wall panel and the beveled surfaces of the cleats when the walls are assembled, and means for holding said ends and side walls in assembled relation.
